(57) **CLAIM**

The ornamental design for eyeglass frames, as shown and described.

DESCRIPTION

FIG. 1 is an isometric view of a left frame of eyeglass frames; FIG. 2 is front view of FIG. 1;

FIG. 3 is a rear view of FIG. 1;

FIG. 4 is a left-hand side view of FIG. 1;

FIG. 5 is a right-hand side view of FIG. 1;

FIG. 6 is a top view of FIG. 1;

FIG. 7 is a bottom view of FIG. 1;

FIG. 8 is an isometric view of a right frame of eyeglass frames;

FIG. 9 is front view of FIG. 8;

FIG. 10 is a rear view of FIG. 8;

FIG. 11 is a left-hand side view of FIG. 8;

FIG. 12 is a right-hand side view of FIG. 8;

FIG. 13 is a top view of FIG. 8;

FIG. 14 is a bottom view of FIG. 8; and,

FIG. 15 is another isometric view of the left frame and the right frame of the eyeglass frames with additional eyeglass framework in the environment for illustration.

The broken lines shown in the drawings illustrate the environment of the article and form no part of the claimed design. The left and right frames are shown separately in FIGS. 1–14 for ease of illustration only.
